DOOR SEAL

Clarence G. Bauer, Berkely, Mich., assignor to
 Chrysler Corporation, Highland Park, Mich., a
 corporation of Delaware

Application July 15, 1947, Serial No. 761,102

6 Claims. (Cl. 296—44)

1

This invention relates to automobile door constructions and has particular reference to a construction permitting the use of the same type of sealing strip around all edges of the door, the strip serving as a means for cushioning the closing of the door, eliminating rattles between the door and the surrounding body frame and providing a substantially airtight seal between the door and the surrounding body frame. The sealing effect between the doors and the surrounding body frame has become of increasing importance due not only to the desire to eliminate drafts within the automobile but also due to the desire to provide a substantially airtight interior for automobiles equipped with interior heaters and so-called air conditioning equipment.

In the past, compression type sealing strips of various designs have been used between the marginal flanges on the doors and the surrounding body frame. Some of the disadvantages of compression type seals are that they interfere with and provide a hard door closing action, often they are inefficient as they seal only at the high points and fail to provide an effective seal at the low points between the door seals and surrounding body frame, and, due to the destructive compressive action, a relatively large size, rugged sealing strip must be provided in order to withstand the wear to which the strip is subjected on door closing movement.

In an effort to overcome the disadvantages of compression type seals, resilient, cantilever type seals have been proposed. The cantilever type seal is of the non-compression type, and, due to the protruding, resilient, sealing finger, which is hingedly connected to the base of the seal so as to be easily bent into sealing engagement with the door jamb, a very soft door closing action is attained. By the use of a cantilever type seal a substantially airtight seal is produced along the entire joint between the door and surrounding frame, regardless of variation in clearance along the joint and, furthermore, a less rugged, cheaper type of seal may be used. The hinging action of the sealing finger in a cantilever type of seal is not as injurious to the seal as is the compressive action in a compression type of seal therefore the life of the cantilever seal is longer than a compression type seal.

One of the difficulties encountered in the use of a cantilever type seal has been the requirement for accurate and proper installation of the sealing strip on the edge of the door. It has been found that a seal of this type must be installed so that the sealing finger can be easily bent out-

wardly to seal against the exteriorly exposed front wall of the door jamb on door closing movement. If the seal is not properly installed on the door the sealing finger may be bent inwardly and compressed between the door and the side wall of the jamb so as to cause a hard door closing action as well as an inefficient seal. Symmetrically shaped, cantilever seals having the sealing finger extending at an angle of forty-five degrees with the horizontal have been found to be the most satisfactory type of seal due to their construction permitting reversibility during installation without interference with their sealing and cushioning properties. It has been found that, unless this cantilever type seal is made symmetrical in cross-section, there is a tendency for the assembly line worker to install it in a reversed or backwards position, that is, with the sealing finger positioned so as to be bent inwardly against the side wall of the door jamb instead of outwardly so as to tension the sealing finger against the exterior front wall of the door jamb. Also, the cantilever type seal must be so designed that the sealing finger has a substantially hinged connection to the base portion which permits a free bending action of the finger about the base portion. Such a construction has excellent sealing and cushioning properties and also gives a flexible seal that can be easily bent about the sharp corners or curved portions of the member on which it is mounted. The particular seal herein referred to is more clearly described in an application of Karl Pfeiffer, Serial Number 760,957, filed July 15, 1947.

35. In the past it has been difficult to use the symmetrically shaped cantilever type of seal around all edges of an automobile door due to the different types of hinging action occurring at the various edges of the door. It is obvious that it is 40 advantageous to use the same type of door seal around all edges of the door. In applying the symmetrically shaped, single cantilever type door seal to the door of an automobile of current design a problem develops which is solved by my 45 novel frame construction. Door constructions of current designs usually have the upper portion of the door curved or sloped inwardly and upwardly towards the roof. This positions the upper portion of the door on the inside of the hinge axis or hinge line, see Fig. 3, whereas the lower portion of the door is on the outside of the hinge line. As a result of this type of construction different regions of the seal along the hinging edge are positioned at different radial distances from 50 the hinge line and accordingly engage the door

jamb at different times during the door closing movement. Due to the hinge mounting generally used with this type of door construction, the lower portion of the hinge edge of the door bends the sealing finger of the door seal, along this lower portion of the door, into engagement with the adjacent portion of the jamb on the door frame before the seal on the upper portion of the hinge edge of the door is moved into sealing engagement with the jamb on the upper portion of the door frame. To further complicate the problem usually the upper portion of the hinge edge of the door slants away from the hinge line, in addition to extending inwardly and upwardly. For instance, the upper portion of the hinge edge of the front door slants upwardly, inwardly and rearwardly whereas the upper portion of the hinge edge of the rear door slants upwardly, inwardly and forwardly. To provide for the use of the improved type of symmetrical, cantilever seal around all edges of a door of current design, it has been found necessary to modify the design of the door jamb along the upper portion of the hinge edge, so as to produce the same type of hinge-like sealing action along this portion of the door edge as occurs along all other portions of the door edge. It has been found that by beveling off the outwardly projecting edge of the door jamb, along the upper portion of the hinge edge, it is possible, on door closing movement, to swing the sealing finger of the door seal outwardly against the adjacent front wall of the door jamb so as to produce the same type of sealing action along this portion of the door edge as occurs along all other edge portions of the door. If the edge of the door jamb along the upper portion of the hinge edge is not beveled off then the sealing finger along this portion of the door will be swung into engagement with the side wall of the door jamb, during door closing movement, and the finger will be bent inwardly and compressed against the side wall of the door jamb, instead of hinged outwardly against the front wall of the door jamb. Dashed lines in Fig. 2 indicate the normal position of the door jamb hinge edges prior to beveling. It is obvious that the sealing finger of the seal would contact the side wall of the jamb and be bent inwardly on door closing movement if the edge of the jamb were not beveled off. If the inward bending action were to occur, the upper and lower ends of the portion of the door seal, along the upper portions of the hinge edge of the door, would contain cross-over sections resulting from the twisting or bending of some portions of the seal inwardly against the side wall of the door jamb and bending other portions outwardly against the front wall of the door jamb. These cross-over sections between the oppositely bent sections of the seal are undesirable for they interfere with the closing of the door due to their functioning as direct compression type sealing strips and, furthermore, due to the internal stresses developed within the twisted sections of the seal, there is a tendency to tear the seal off the door along the cross-over regions. If the sealing finger is bent inwardly against the side wall of the door jamb instead of outwardly against the front wall of the door jamb, then a poor seal is produced for snow, ice and rain can partially penetrate the joint between the door and the surrounding body frame and cause trouble. By the simple expedient of beveling the edge of the door jamb, along the upper portion of the hinge edge of the door, it is possible to use the same type of door

seal along all edges of the door, have all sections of the door seal function in the same way so as to produce an efficient seal, and eliminate cross-over sections which are detrimental to the seal as well as a source of hard door closing action.

The seal on all sides of the door, other than along the hinging edge, is far enough removed from the door hinge line or axis to be bent into sealing engagement with the front wall of the adjacent door jamb on door closing movement.

It is a principal object of my invention to provide a door construction in which the same type of symmetrical, cantilever door seal may be applied to all edges of the door, the door frame and seal being so constructed and arranged that an improved seal is attained, installation of the door seal is simplified, and overall cost of the door construction reduced.

It is another object of my invention to provide a door construction of an improved and simplified design which provides a substantially airtight seal, eliminates rattles between the door and surrounding body, and provides an easy door closing action.

It is another object of my invention to provide a door frame construction for use with a door having the same type of cantilever door seal mounted about all its edges, the door jamb along the hinge edge being beveled so as to insure an efficient seal about all edges of the door and also providing an easy door closing action as well as an economical, simplified construction.

Other objects and advantages will become apparent from the following description of my improved seal when considered in conjunction with the drawings in which:

Fig. 1 is a side view of an automobile equipped with a door cushioning and sealing means in accordance with my invention;

Fig. 2 is an enlarged sectional view taken along the line 2—2 of Fig. 1, indicating the position of the sealing fingers after closing of the doors, portions of the front door being broken away to more clearly disclose my invention;

Fig. 3 is an end view of a door of current design which illustrates the relationship of the upper and lower portions of the door with respect to the hinge axis or hinge line; and

Fig. 4 is a sectional view through an edge of a door having a symmetrical, cantilever type sealing strip mounted thereon, the sealing finger being shown in its normal open door position.

Each of the doors 10, mounted on the usual hinges 11, is, in accordance with my invention, provided with a cushioning and sealing strip 12, mounted on the side edges of the doors inside the marginal flanges 13 at the exterior side of the doors. The front door is hingedly mounted on the A post of the body and the rear door is hingedly mounted on the center or B post of the body frame. The door frame 14 has a continuous marginal recess 15 around each of the doors adapted to receive the flange 13 of the door 10 so that the outside of the door is substantially flush with the outside of the body when the door is closed. The flush relationship between the door and body is preferably maintained at all points except along the top of the door, the body being preferably formed at that location to project outwardly beyond the plane of the door so as to provide an eave to prevent drainage into the joint between the door and the body. The door frame 14 provides the door jamb 22 which extends into the recess 15 and affords a front sealing wall 23 to be engaged by the sealing strip 12, and a side wall

24 adapted to overlie the side edge 17 of the door. The upper portion of the door jamb along the hinging edge of each door has a beveled projecting edge 25. It is necessary to bevel off this portion of the edge of the door jamb for this edge portion of the jamb is inside the hinge line, see Fig. 3, and it would interfere with the sealing action of the sealing finger 19 of the seal 12 on door closing movement if it were not beveled off. Instead of using a separate, special type of seal along the hinge edges of the doors, by beveling off the portion of the jamb along the hinge edge that is inside the hinge line, it is possible to use the same type of seal around all edges of the doors. By applying the same type of seal to all edges of the doors, installation is simplified, less labor is expended and costs are reduced. The beveling of the door jamb can be formed with the stamping of the body frame so no substantial cost increase results from the use of a beveled hinging edge along the door jamb. The sealing strip 12 will ordinarily be provided around all edges of each door, the continuity of the strip being indicated by dashed lines in Fig. 1. The strip 12 is preferably of molded sponge rubber or some similar resilient material and can be formed with an outer skin on its exposed surfaces to improve its wearing characteristics. The sealing strip 12 is cemented, or otherwise suitably secured by pins, wires, clips or the like to the inside wall 16 of the door flange 13 and to the edge 17 of the door 10. The seal 12 is formed in cross section to be symmetrically shaped and has a right angled base portion 18 adapted to be seated in the corner between the door flange 13 and the side edge 17 of the door. In cross section this base portion 18 is substantially of a right-angled, isosceles triangular configuration having the rear side 20 extending at forty-five degrees with both the horizontal wall 17 and the vertical wall 13 which it intersects. This base in cross section resembles an arrowhead and is adapted to have the point or vertex seated in the corner between the flange 13 and edge 17. Extending outwardly from the medial portion of the rear side 20 of the symmetrical base portion 18 of the seal, along a line which bi-sects the angle between the sides of the base portion 18, is a long, symmetrically shaped, sealing finger 19. The dimensions and shape of sealing finger 19 are such as to furnish a relatively narrow throat portion 21 in order to provide the necessary hinging action between the sealing finger 19 and the base portion 18. The long sealing finger 19 insures a perfect seal regardless of the variations in clearance between the door and frame. Due to the symmetrical design of the sealing strip 12, it is obvious that regardless of the way in which the base portion 18 of the sealing strip 12 is placed in the corner between the side edge 17 and the marginal flange 13 of the door, the sealing finger 19 will always project at the same angle and consequently will always function in the same manner. The combination of a symmetrical cantilever seal with a door jamb having the portion of the jamb within the hinge line, along the hinge edge, beveled off, eliminates the possibility of the sealing finger 19 being bent inwardly and compressed against the door jamb side wall 24 on door closing instead of being bent outwardly and tensioned against the front wall of the door jamb 22.

I claim:

1. In an automobile door construction, a door frame defining a door opening and having a jamb portion providing an exteriorly exposed front wall

and a side wall, the door jamb along the hinge edge of the door frame comprising a lower hinge portion positioned on the outside of the hinge line and an upper portion positioned on the inside of the hinge line, the intersecting edge of the front and side walls of the door jamb along the upper portion of the hinge edge being beveled off, and a door, shaped to conform to the door opening, hingedly mounted on the lower hinge portion of said door jamb, said door having a resilient, symmetrically shaped, cantilever type door seal comprising a base portion and a sealing finger projecting therefrom mounted on its marginal edges, the sealing finger on said seal being adapted to engage and seal against the front wall of said door jamb on door closing movement.

2. In an automobile door construction, a door frame defining a door opening and having a jamb portion providing an exteriorly exposed front wall and a side wall, the door jamb along the hinge edge of the door frame comprising a lower hinge portion positioned on the outside of the hinge line and an upper portion positioned on the inside of the hinge line, the intersecting edge of the front and side walls of the door jamb along the upper portion of the hinge edge being beveled off, and a door, shaped to conform to the door opening, hingedly mounted on the lower hinge portion of said door jamb, said door having a marginal flange adapted to overlie the front wall of said door jamb when said door is closed, and a symmetrically shaped, cantilever type door seal of resilient material mounted on the side edge of said door adjacent the inner side of said marginal flange, said seal having an outwardly extending sealing finger adapted to engage and seal against the front wall of said door jamb on door closing action.

3. In an automobile door construction, a door frame defining a door opening and having a jamb portion providing an exteriorly exposed front wall and a side wall, the door jamb along the hinge edge of the door frame comprising a lower hinge portion positioned on the outside of the hinge line and an upper portion positioned on the inside of the hinge line, the intersecting edge of the front and side walls of the door jamb along the hinge edge of the door frame being beveled off, and a door, shaped to conform to the door opening, hingedly mounted on the lower hinge portion of said door jamb, said door having a resilient, cantilever type door seal comprising a base portion and a sealing finger projecting therefrom mounted on its marginal edges, the sealing finger on said seal being adapted to engage and seal against the front wall of said door jamb on door closing movement.

4. In an automobile door construction, a door frame defining a door opening and having a jamb portion providing an exteriorly exposed front wall and a side wall, the door jamb along the hinge edge of the door frame comprising a lower hinge portion positioned on the outside of the hinge line and an upper portion positioned on the inside of the hinge line, the intersecting edge of the front and side walls of the door jamb along the hinge edge of the door frame being beveled off, and a door, shaped to conform to the door opening, hingedly mounted on the lower hinge portion of said door jamb, said door having a marginal flange adapted to overlie the front wall of said door jamb when said door is closed, and a cantilever type door seal of resilient material mounted on the side edge of said door adjacent the inner side of said marginal flange, said

seal having an outwardly extending sealing finger adapted to engage and seal against the front wall of said door jamb on door closing action.

5. In an automobile door construction, a door opening having a jamb portion along the hinging edge of the opening providing an exteriorly exposed edge, the lower portion of said edge being positioned outside the hinge axis and the upper portion of said edge being positioned within the hinge axis, the edge at said upper portion of said jamb being beveled, and a door, shaped to conform to said opening, hingedly mounted on the lower portion of the hinging edge of said jamb, said door having a resilient, cantilever type sealing strip comprising a base portion and a sealing finger projecting therefrom mounted about its marginal edges, the sealing finger of said sealing strip being adapted to engage the exteriorly exposed edge of said jamb and to be bent outwardly on movement of the door to closed position.

6. In an automobile door construction, a door frame defining a door opening and having a jamb portion providing an exteriorly exposed front wall and a side wall, the door jamb along the hinge edge of the door frame comprising a portion posi-

5
